INSULATING BUSHING FOR A LEAD-IN CONDUCTOR TO A CAPACITOR HOUSED IN A VESSEL CONTAINING A GAS UNDER PRESSURE

Cornelis de Lange, Eindhoven, Netherlands, assignor to Hartford National Bank and Trust Company, Hartford, Conn., as trustee

Application July 20, 1946, Serial No. 685,173
In the Netherlands February 17, 1943Section 1, Public Law 690, August 8, 1946
Patent expires February 17, 1963

5 Claims. (Cl. 174—18)

1

This invention relates to an electric device, more particularly a condenser placed in a gas-filled pressure vessel, a supply conductor of which is led through the wall of the vessel in a gas-tight and insulated manner by means of a ceramic intermediate piece and is supported outside the vessel by a lead-in insulator which concentrically surrounds the supply conductor and whose base is fastened to the wall of the vessel.

For improving the power factor in transmission lines use is frequently made of pressure condensers when large powers are concerned. In this case the condenser is housed in a pressure vessel filled with gas, for example nitrogen, up to a pressure of 20 atmospheres. The breakdown voltage and the security in operation of the condenser appreciably increases by the use of gas under pressure. In most cases such a construction utilises welded sheet steel for the pressure vessel. It is then necessary for at least one of the supply conductors to be led through the wall of the vessel in a gas-tight and insulated manner. A ceramic intermediate piece arranged in a gas-tight manner is particularly suitable for the purpose. To this type belongs the known glass-chrome iron lead-in device. In this case a chrome-iron cylinder is welded in an aperture of the wall, a chrome-iron ring being fastened on the supply conductor. The cylinder and the ring are now connected to each other by means of glass having a suitable coefficient of expansion. This construction is not sufficiently rigid without further expedients. Consequently, it is necessary for the supply conductor to be supported outside the vessel, so that any forces exerted thereon need not be taken up by the glass intermediate piece. For support use is frequently made of a lead-in insulator which concentrically surrounds the supply conductor and whose base is secured directly or indirectly to the wall of the vessel. The supply conductor is fastened in the lead-in insulator, so that forces exerted on the supply conductor are taken up by the lead-in insulator. The latter is of the known type and is made of porcelain.

Pressure condensers have the drawback of the danger of explosion. It is not difficult for the vessel containing the condenser to be constructed so rigidly that the risk of breakage thereof is practically precluded. The glass intermediate piece necessary for the gas-tight and insulated entry of a supply conductor through the wall forms, however, the weakest point of the vessel. If here pressure occurs, the lead-in insulator arranged outside the vessel will also be exposed to

2

the pressure prevailing in the vessel. Since the dielectric losses must be small, this lead-in insulator has a small wall thickness, so that it cannot resist the high pressure which occurs in the case of breakage of the intermediate piece. The fragments of this insulator and of the glass intermediate piece will now be flung away by the force of the escaping gases. In this case there is a danger to apparatus which may be present and a risk of damage to the other parts of the installation in the vicinity of which the condenser is located.

The present invention has for its object to eliminate the said drawbacks by providing a construction which offers great safety.

According to the invention, the space located between the ceramic intermediate piece and the lead-in insulator is shut off from the atmosphere by means of a membrane which is not able to resist the pressure normally prevailing in the pressure vessel. If, now, breakage of the ceramic intermediate piece occurs, the space located between the intermediate piece and the lead-in insulator will be filled with gas under high pressure, so that the membrane will break down. The gases now break a way and the lead-in insulator is not exposed to a high pressure, so that any action of fragments is avoided.

In one advantageous embodiment of the invention a saving in space is obtained wherein the membrane exhibits a flat annular shape and is secured between the supply conductor and the ring which concentrically surrounds the latter and is fastened to the lead-in insulator.

There is still a small possibility that the lead-in insulator breaks or at least is damaged by fragments of the intermediate piece, which, when the latter is broken, are taken along by the gas flow. In one advantageous embodiment of the invention, in order to avoid or at least to reduce the action of fragments upon a lead-in insulator, a partition is arranged between a glass intermediate piece and the lead-in insulator and concentrically about the supply conductor. It has been found, that in the case of breakage this partition reduces the action of fragments in such manner that breakage of the lead-in insulator is no longer to be feared. However, it is also possible for this partition to be made from so tough a material and/or of such thickness that in the case of breakage of the intermediate piece it is completely resistant to the action of fragments.

It is evident that the partition must not prevent the passage of the gases. To this end, it may comprise apertures or it may not extend as

far as the wall. In one advantageous embodiment of the invention, the partition has an aperture provided in it concentrically around the supply conductor. It is thus ensured that the partition must not necessarily exhibit excellent insulating properties whilst a decrease of the creeping distance is out of the question.

In order that the invention may be more clearly understood and readily carried into effect, it will be described more fully by reference to 10 the accompanying drawing.

Fig. 1a is a cross-sectional view of the lead-in construction according to the invention for a pressure housed capacitor; and

Fig. 1b is a top view of the device shown in 15 section in Fig. 1a.

Referring to Fig. 1a, the steel wall 1 of the vessel has a chrome-iron cylinder 2 welded in it. The latter is connected, by means of a glass intermediate piece 3, to a chrome-iron ring 4 soldered to the supply conductor 5 which is thus led through the wall 1 in a gas-tight and insulated manner. To avoid spraying, screening rings 18, 19, 20 and 21 are provided. In order to mechanically discharge the intermediate piece 3, the supply conductor 5 is supported outside the vessel by a lead-in insulator 6, the base 7 of which is fastened to the wall 1 by means of a flange 8 of the chrome-iron cylinder 2. The lead-in insulator 6 has arranged on it a metal ring 9 which, by means of a number of spokes 10, 11, 12 and 13 (see Fig. 1b), is connected to a ring 14 arranged on the supply conductor 5. The lead-in insulator 6 takes up, via the spokes, the forces exerted on the supply conductor. The membrane 15 is secured between the ring 9 and the supply conductor 5. Between the intermediate piece 3 and the lead-in insulator 6 is arranged the partition 16 which exhibits an aperture 17 provided concentrically about the supply conductor 5. In the case of breakage of the intermediate piece 3 the partition 16, which may be, for example, of a low-loss ceramic material, intercepts the fragments, which may also result in a breakage of the partition itself. Due to the pressure of the gases, the membrane 15 collapses, so that the lead-in insulator 6 is exposed to a slight over-pressure. Consequently, in the case of breakage of the intermediate piece 3, externally no fragments occur. If the partition 16 is so proportioned and/or manufactured from such material that it does not break as a result of breakage of the intermediate piece 3, an additional advantage may be obtained by giving the resistance of flowing of the aperture 17 a high value relatively to that of the aperture closed by the membrane 15. In the case of breakage the greater part of the difference in pressure between the interior and the exterior of the vessel then acts upon the aperture 17, and the remaining portion on the aperture adjacent to the membrane 15. The pressure in the space located between the partition 16 and the insulator 6 thus remains low.

Condensers according to the invention are completely free from any action of fragments and thus particularly advantageous to be housed in spaces in which operating staff must always be present and/or vulnerable devices are arranged.

What I claim is:

1. An insulating bushing for a lead-in conductor extending into a housing for a condenser and the like containing a gas under pressure comprising an insulating protective member interposed between the walls of the housing and

the lead-in conductor, a gas-tight member interposed between the protective member and the lead-in conductor, a hollow insulating supporting member exterior to and secured to the housing and concentric with the lead-in conductor which defines an enclosed space between it and the protective member, and a collapsible membrane interposed between the supporting member and the lead-in conductor which collapses when the pressure prevailing in the space between the supporting member and the protective member exceeds that normally prevailing therein.

2. An insulating bushing for a lead-in conductor extending into a housing for a capacitor and the like containing a gas under pressure comprising an insulating protective member interposed between the walls of the housing and the lead-in conductor, a gas-tight member interposed between the protective member and lead-in conductor, a hollow dome-like insulating supporting member exterior to and secured to the housing and concentric with the housing, an annular ring-like member securing said lead-in conductor to said supporting member, and a collapsible member interposed between the ring-like member and the lead-in conductor which collapses when the pressure prevailing in the space between the supporting member and the protective member exceeds that normally prevailing therein.

3. An insulating bushing for a lead-in conductor which extends into a housing for a capacitor and the like containing a gas under pressure comprising an insulating protective member interposed between the walls of the housing and the lead-in conductor, a gas-tight member interposed between the protective member and the lead-in conductor, a hollow dome-like insulating supporting member exterior to and secured to the housing and concentric with the lead-in conductor, an annular ring member for securing the lead-in conductor to the supporting member, a flat annular membrane interposed between the lead-in conductor and the supporting member which collapses when the pressure prevailing in the space between the dome-like supporting member and the protective member exceeds that normally prevailing therein, and a protective partition concentric with said lead-in conductor and interposed between the latter and the protective member.

4. An insulating bushing for a lead-in conductor which extends into a housing for a capacitor and the like containing a gas under pressure, comprising an insulating protective member interposed between the walls of the housing and the lead-in conductor, a gas-tight member interposed between the protective member and the lead-in conductor, a hollow dome-like insulating supporting member exterior to and secured to the housing and concentric with the lead-in conductor, an annular ring-like member for securing the lead-in conductor to the supporting member, a flat annular membrane interposed between the lead-in conductor and the supporting member which collapses when the pressure in the space between the supporting member and the protective member exceeds that normally prevailing therein, and a protective partition interposed between the lead-in conductor and the protective member having an aperture therein which is concentric with the lead-in conductor.

5. An insulating bushing for a lead-in conductor which extends into a housing for a capac-

itor and the like containing a gas under pressure comprising a ceramic member interposed between the walls of the housing and the lead-in conductor, a gas-tight member interposed between the ceramic member and the lead-in conductor, a hollow dome-like insulating supporting member exterior to and secured to the housing and concentric with the lead-in conductor, an annular ring-like member for securing the lead-in conductor to the supporting member, a flat annular membrane interposed between the ring-like member and the lead-in conductor which collapses when the pressure prevailing in the space between the supporting member and the protective member exceeds that normally prevailing therein, a partition of material resistant to fragmentation of the ceramic member in-

terposed between the lead-in conductor and the ceramic member and having an aperture therein concentric with the lead-in conductor and dimensioned to restrict the flow of gas therethrough when the ceramic member shatters.
